UNITED STATES PATENT OFFICE.

OTTO J. KUELKE, OF AKRON, OHIO, ASSIGNOR TO THE KUELKE MACHINE COMPANY,
OF AKRON, OHIO, A CORPORATION OF OHIO.

VULCANIZER.

Application filed April 1, 1926. Serial No. 98,970.

This invention relates to vulcanizers, and while it is designed particularly and especially for the vulcanization of endless elastic bands such as tire flaps, the principles of 5 the invention may be extended for other purposes and for wider utility.

The object of the invention is to construct 10 a vulcanizer for the curing of trough-shaped rubber-flaps, the invention having to do with a mechanism which will be quickly and easily operated and which will uniformly vulcanize the flaps in a short space of time and without loss of material.

In the drawings and description there is 15 shown one form of the invention, it being understood that changes and modifications may be made within the scope of the invention as set forth in the claims attached hereto.

20 Of the accompanying drawings:

Figure 1 is a side elevation of the improved vulcanizer;

Figure 2 is a front elevation thereof when closed;

25 Figure 3 is a front elevation when open; and

Figure 4 is a vertical diametral section therethrough.

The vulcanizer of the present invention 30 comprises a drum or form which is provided with a circumferential trough or channel of the shape of the inner surface of the band of elastic material or tire flap. About the drum is arranged an expansible jacket which 35 is provided with mechanism by which the jacket is opened and closed and at the same time spaced from the drum. The jacket is provided with a rib shaped to correspond to the outer surface of the band and to enter 40 within the channel. A second fixed circumferential jacket is arranged to engage with the inner periphery of the drum. The drum is provided with expansible chambers or air bags which exert pressure upon the material 45

to shape it properly and the jackets are formed with chambers adapted to receive steam for vulcanization, although other heating arrangements may be made. The drum is rotatably mounted and is also 50 slidably mounted so as to be movable from between the jackets, as will be explained, to facilitate the placing of the uncured flap and the removal of the completely vulcanized flap from the machine.

The mechanism herein shown comprises a 55 base member 1 which is provided with the vertical standard 2 which supports the various elements of the device. At the center of the standard is arranged a bearing 3 in which is secured the horizontal shaft 4 60 which projects outwardly beyond the standard and slidably supports the drum or form 5, which is movable upon the shaft in the manner stated so as to permit the easy insertion and removal of the flap. The drum 5 65 is freely rotatable on the right end of shaft 4 (Figure 4), but is adapted to be keyed to the other end of shaft 4 by key 4^a for a purpose to be explained. The drum is provided with an outer peripheral portion 6 which is 70 formed with a central groove or channel 7 of the shape of the flap.

Lying within the enclosed side walls of 75 the channel are two expansible wall members or air bags 8 adapted to be inflated by air or other fluid under pressure through valves 9. A strip of covering material 14 may be placed over the bags to cover the cracks at the sides of the bags and afford a smooth 80 surface. Pressure is transmitted to these 80 air bags through flexible pipes 10 which are connected by a T-coupling 11 to a passage-way 40 through the shaft which receives the air under pressure from an air inlet pipe 12 which passes through the central shaft 4. 85 By connecting the bags flexibly the air connections do not interfere with the free rotation or sliding of the drum, the drum being shown in light dotted lines in Figure 1 in the curing position, the stripping position 90 being shown in heavy dotted lines. In order to relieve any strain upon the pipes 10 in the rotation of the drum, the coupling 11, which is swiveled in the end of the shaft, carries a rod or closed pipe 41 which passes through a hole 42 in one of the drum spokes. 95 This operates as a dog to turn the coupling with the drum.

The outer jacket 15 of the machine is in 100 the form of two semi-circular casings or plates provided upon their inner faces with a projecting rib 16 which enters the groove and forms the outer surface of the molding cavity. The jackets 15 are chambered, as 105 shown at 18, for the reception of steam, the inlet and drain pipes for which are shown at 19 and 20, respectively.

The two parts of jacket 15 are hinged to

gether at the base of the machine by a pin 21 passing through the lugs 22 on the jacket, one of the lugs being extended to and pivoted at 23 upon a support 24 situated at the base of the machine; so that the whole jacket is pivotally supported on the base.

The two jacket sections 15 are adapted to be opened and closed and simultaneously moved away from or toward the drum, the 10 double pivotal arrangement of the jacket sections permitting this result. In order to move the jacket sections each one is provided with a lug 28 to which is pivotally connected a curved rack 29, the two racks being 15 oppositely faced and lying upon either side of and meshing with an operating pinion 30 carried upon a crank shaft 31, which is rotatably mounted in a bracket 32 secured to the upper end of the upright 2. As the cr 20 31 is rotated the jacket sections will open and close between the positions shown in Figures 2 and 3, it being observed that in the position shown in the latter or open view the drum 5 may be drawn outwardly along the 25 shaft to the position where it is most easily operated upon. The last tooth of each rack is enlarged and operates as a stop or means for suspending the jacket sections in open position.

30 In order to clamp the jacket sections 15 together, any suitable mechanism may be provided. For this purpose, I have shown a swinging link 34 attached to one of the jacket sections and having a swinging cam 35 lock 35 at its free end receivable over the lug 36 upon the end of the other jacket section. A tight clamping of the two jacket sections is thereby attained.

The inner circumferential heating jacket is 40 shown at 37 and comprises an annular casting bolted to standard 2 and having a slot therethrough at 38 through which the inner air bag connection 10 may extend. The key 42 is adapted to position drum 5 properly so 45 that this connection may extend through slot 38 when drum 5 is moved between jackets 15 and 37. The outer surface of jacket 37 is tapered as at 39 and the inner surface of drum 5 is tapered as at 43 to 50 facilitate sliding of drum 5 into seating relationship on inner jacket 37. Jacket 37 is chambered as at 44 and is connected to a source of steam at 45, 45 and to a drain at 46. The inner jacket 37 is for the purpose 55 of heating the inner portion of the jacket 6 so that the under surface of the flap is thoroughly vulcanized.

The operation and advantages of the device will be readily understood by those 60 skilled in the art, and it will be observed that detailed adherence to the exact construction is not necessary to obtain the full benefits of the invention. In the manufacture of flaps, the operator, having moved 65 the drum to the outer end of the shaft 4,

places a band of unvulcanized rubber upon the drum. When the rubber is properly positioned, the drum is moved backwardly into seating relationship on the inner jacket in line with the outer jacket sections, which 70 are open in the position shown in Figure 4. Rotation of the crank 31 moves the jacket sections together and raises them to closed position and the jacket is locked by the device 34. Air pressure is then admitted to 76 the bags 8 by opening the cock 13, and steam being admitted to the jackets, the flap is cured between the hot surface of the jackets and the air bags while being heated from within by the inner jacket. A reversal of 80 the operations permits the removal of the cured flap which will be found to be perfectly cured to shape, without waste.

Modifications of the invention may be resorted to without departing from the spirit 85 thereof or the scope of the appended claims.

What is claimed is:

1. In an apparatus of the character described, a support, a vertical form slidably and rotatably mounted upon the support, a sectional jacket adapted to surround the form, means for opening and closing the jacket, and a second jacket about the inner periphery of the form. 90

2. In an apparatus of the character described, a horizontal shaft, a form slidably mounted upon the shaft, a sectional jacket surrounding the form, means to open and close said jacket, and a second jacket about the inner periphery of the form. 95

3. In an apparatus for vulcanizing tire flaps or the like, a vertical form having a groove upon its outer periphery, a sectional jacket about the form, means for opening the jacket and removing it from contact 100 with the form, and a second jacket about the inner periphery of the form, the form being mounted so as to be movable toward and from the jackets. 105

4. In an apparatus for vulcanizing tire flaps or the like, a vertical rotatable form having a groove upon its outer periphery, a sectional jacket about the form, means for opening the jacket and removing it from contact with the form, and a second jacket 110 about the inner periphery of the form. 115

5. In an apparatus for vulcanizing the flaps or the like, a circular form having a substantially V-shaped cavity in its periphery, a sectional jacket about the form, a rib upon the inner surface of the packet and adapted to enter the cavity, a second jacket about the inner periphery of the form, and an expansible air bag seated within the form and constituting an inclined wall thereof. 120

6. In an apparatus for vulcanizing tire flaps or the like, a circular form having a substantially V-shaped cavity in its periphery, a sectional jacket about the form, a second jacket about the inner periphery of 125 130

the form, and an expansible air bag seated within the form and constituting a wall of the cavity.

7. In an apparatus for vulcanizing tire flaps or the like, a circular form having a substantially V-shaped cavity in its periphery, a sectional jacket about the form, a second jacket about the inner periphery of the form, and expansible air bags lying

10 within a wall of the cavity.

8. In an apparatus of the character described, a circular form, an expansible bag within the form and forming one wall of a vulcanizing cavity therein, a shaft upon 15 which the form is slideable, a flexible conduit to the bag, an expansible chambered jacket surrounding the form, means for conducting steam to the jacket, a second chambered jacket about the inner periphery of the 20 form, means for conducting steam to the second jacket, and mechanism adapted to expand the jacket and simultaneously lower it away from the form.

9. In an apparatus of the character described, a circular form, an expansible bag within the form and forming one wall of a vulcanizing cavity therein, a shaft upon 25 which the form is slideable and rotatable, a flexible conduit to the bag, an expansible chambered jacket surrounding the form, means for conducting steam to the jacket, a second chambered jacket about the inner periphery of the form, means for conducting steam to the second jacket, and mechanism adapted to expand the first jacket and simultaneously lower it away from the form.

10. Apparatus of the class described, comprising concentric inner and outer circumferential jackets, said outer jacket being expandable, and a circumferential form axially movable between the jackets into seating relationship on the inner jacket into position such that the outer jacket may be contracted thereon.

45 11. Apparatus of the class described, comprising concentric inner and outer circum-

ferential heating jackets, and a circumferential form axially movable between the jackets, said form having a molding cavity in one periphery thereof, one of said jackets 50 having a molding surface for extending into said cavity, said last-mentioned jacket being expansible and contractible so as to move said molding surface into or out of said cavity.

12. Apparatus of the class described, comprising a vertically supported inner, annular heating jacket, a concentric vertically supported outer, expansible, annular heating jacket, and a form axially slideable between 55 said jackets, the outer surface of the first jacket and the inner surface of the form being tapered so that the latter may be urged into seating relationship on the former in line with the outer jacket.

13. In an apparatus for vulcanizing tire flaps or the like, a circular form having a vulcanizing cavity in its periphery, a sectional jacket about the form, an expansible air bag lying within a wall of the cavity, 70 and means for heating the material within the cavity comprising an inner circumferential jacket.

14. Apparatus of the class described, comprising concentric inner and outer circumferential jackets, a circular form provided with a peripheral cavity and movable between the jackets, and an air bag in said cavity, said inner jacket being chambered 75 for the reception of a heating medium.

15. Apparatus of the class described, comprising an inner circumferential jacket formed with a slot therein, a shaft concentric with said jacket, a circular form shiftable onto said jacket and rotatable on said 85 shaft, a pressure bag in said form, and a connection extending to said bag, said shaft having means thereon for aligning said connection with said slot when said form is shifted onto said jacket.
